UNITED STATES PATENT OFFICE.

ROBERT G. HOPKINS, OF SOMERVILLE, ASSIGNOR TO THE CARTER, DINSMORE & COMPANY, OF BOSTON, MASSACHUSETTS, AND NEW YORK, N. Y.

RIBBON-CASE FOR TYPE-WRITING MACHINES.

SPECIFICATION forming part of Letters Patent No. 530,307, dated December 4, 1894.

Application filed July 30, 1892. Serial No. 441,711. (No model.)

To all whom it may concern:

Be it known that I, ROBERT G. HOPKINS, a citizen of the United States, residing at Somerville, in the county of Middlesex, State of Massachusetts, have invented a new and useful Improvement in Type-Writer-Ribbon Cases, of which the following is a full, clear, and exact description, reference being had to the accompanying drawings, forming a part of this specification, in explaining its nature.

The invention relates to a case for holding, transporting and delivering typewriter ribbons of the character used upon the Hammond, Crandall and similar typewriting machines, and it is adapted to take the place of the ribbon holder or reels of such machines. In such capacity it not only acts as a cover and protector for the ribbon, but also as a means by which it can be used in the machine.

Referring to the drawings, Figure 1 is a view in perspective, representing the application of my invention to a Hammond type-writing machine. Fig. 2 is a view in vertical section through the ribbon case and ribbon. Fig. 3 is a view representing the cover as removed from the case or ribbon holding section or part. Fig. 4 is a view in plan of the ribbon holding part. Fig. 5 is a view in perspective of the turning crank.

The case or holder comprises two sections, namely, the part A, having a hub or sleeve on which the ribbon is mounted, and comprising a plate having extending upward from its center a bearing to fit the ribbon reel spindles or shafts of the Hammond or other machines, a sleeve about said bearing forming a space for receiving and holding a ribbon end, and means at its outer edge for receiving and holding the other section of the

case or holder, namely, the section A', which is of a shape to cover one side and the outer edge of the ribbon, and to be united at its lower edge to the first named section.

It will be observed that when the section A' is removed from the section A the ribbon remains upon the sleeve so that it may be readily unwound from it, being unrestrained upon its side.

The section A, preferably, is made of sheet metal, and the bearing a is preferably formed

by striking up or spinning the center section of the blank from which this part is made, the bearing sleeve a preferably being integral with the bottom a', and being of a size to fit the ribbon shaft, spindle or support of the machine for which the ribbon is adapted.

The outer edge of the section A is preferably provided with a V or cup-shaped channel a² below the upper surface of the bottom a' to receive and hold the lower edge of the covering section. The section A also has the sleeve a³, which is united to the bottom a' of section A, and which surrounds the central sleeve a and is of a size sufficient to form a narrow recess or chamber a⁴. This sleeve a³ has preferably a slit a⁵, through which one end of the typewriter ribbon is passed, the hooks or devices by which the ribbon is attached to a roll or reel being contained in the recess a⁴, and acting to hold the inner end of the ribbon to the sleeve. The ribbon is then wound about this sleeve by turning the section A, which may be supported on a suitable shaft or spindle, the edge of the ribbon of course resting upon the bottom a' as it is wound. The section is adapted to be turned by means of a crank B, which fits the upper end of the sleeve a³, which is somewhat drawn in at that point to form a shoulder a⁶ against which the crank ring b may rest. The crank ring has also a projection or spur b' which extends into the upper end of the slit a⁵, which is somewhat enlarged preferably to receive it. From the ring there extends the crank arm b². This when the case is closed for transportation is turned downward, as represented in Fig. 2. In use its position is reversed, or as represented by the dotted lines in Fig. 3.

The cover section A' has the top c provided with a central recess c' of a size to fit upon the upper edge or section of the sleeve a³, and it also has the cylindrical section c², which is of a size to cover the wound ribbon, and is of a depth sufficient to cover it and permit its lower edge c³ to extend into the cup or V-shaped recess a², and this edge c³ preferably has bayonet recesses c⁴ either cut or pressed therein with which the projections c⁴⁰ of the sections A engage. (See Fig. 3.) This

bayonet slot is in effect a screw fastening, but I do not confine myself to this method of securing the two sections of the case together.

The case thus formed provides a reel for the ribbon and a cover for it which serves to protect and cover it while it is being transported and exposed for sale, and in use the base section may serve as the reel of the typewriting machine or not, as desired. When so employed it is placed on the holding spindle shaft say of a Hammond machine, (see Fig. 1,) and the section A' removed. The ribbon is then exposed and is held by the sleeve and bottom a', and in a position to render or deliver to the other reel of the machine. There may then be used to rest upon and protect the ribbon from dust a thin flat plate e. (See Fig 1.)

It will be observed that the cup or recess for receiving and holding the flange of the cover A' is below the bottom a' and therefore does not interfere with the delivery of the ribbon from the sleeve or with its winding thereon.

25 When the ribbon holder is used on a Crandall machine it will be necessary, of course, to provide the bottom section with an exterior gear.

Having thus fully described my invention, 30 I claim and desire to secure by Letters Patent of the United States—

1. A typewriter ribbon case or holder comprising the section A having an upward extending sleeve or bearing, and the cover A' having the top c, and cylindrical section c², the said section A having a groove or recess

near its edge to receive the edge of the said cylindrical section c² as and for the purposes described.

2. The combination in a typewriter ribbon 40 case or holder, of the section A, the bearing a, the slit sleeve a³ and the downward cover holder section a² with the cover A', having the top c and flange c³ adapted to be united with the flange a² of the section A, as and for the 45 purposes described.

3. A typewriter ribbon holder comprising the section A having the bearing or sleeve a and the ribbon holding sleeve a³, and flange a² below the bottom a' with the cover A' having 50 the section c' to fit the sleeve a³, and the flange c³ adapted to be united to the flange a², as and for the purposes described.

4. The typewriter ribbon holder having the ribbon holding sleeve or hub provided with 55 a shoulder a⁶ and a recess or opening, combined with a crank to fit said sleeve and rest against the shoulder thereof and provided with a spur adapted to engage said recess, substantially as described.

5. The typewriter ribbon holder having the base or bottom a' and a ribbon holding hub or sleeve rising therefrom and having a vertical slit, combined with a crank consisting of an annular ring adapted to encircle the 65 hub and having a projection to enter said slit therein, and the handle b², substantially as described.

ROBERT G. HOPKINS.
